United States Patent Office

Des. 230,561
Patented Mar. 5, 1974

230,561

WIRE STRIPPER

Fred D. Blackwell, 14 Parklin St.,
North Providence, R.I. 02907

Filed Sept. 13, 1971, Ser. No. 177,188

Term of patent 14 years

Int. Cl. D8—03

U.S. Cl. D8—99

FIG. 1

FIG. 2

FIG. 3

FIG. 4

FIG. 5

FIG. 1 is a side elevational view of a wire stripper embodying my new design, the broken lines showing the blade in closed position;

FIG. 2 is a top plan view thereof;

FIG. 3 is a bottom plan view thereof;

FIG. 4 is an end elevational view thereof, looking from the right with respect to FIG. 1; and

FIG. 5 is an end elevational view thereof, looking from the left with respect to FIG. 1.

I claim:

The ornamental design for a wire stripper, substantially as shown.
